UNITED STATES PATENT OFFICE.

FREDERICK J. RADFORD, OF TRINIDAD, COLORADO.

SELF-OILING CAR-WHEEL.

SPECIFICATION forming part of Letters Patent No. 687,651, dated November 26, 1901.

Application filed April 26, 1901. Serial No. 57,585. (No model.)

To all whom it may concern:

Be it known that I, FREDERICK J. RADFORD, a citizen of the United States, residing at Trinidad, in the county of Las Animas and State 5 of Colorado, have invented new and useful Improvements in Self-Oiling Car-Wheels, of which the following is a specification.

My invention has for its object to provide a self-oiling car-wheel which while equally as 10 efficient is a material simplification of those extant, and its novelty and advantages will be fully understood from the following description and claim when taken in conjunction with the accompanying drawings, in which—

15 Figure 1 is a diametrical section of my improved wheel with the exterior lugs of the cap partly in elevation. Fig. 2 is a perspective view of the body or main portion of the wheel, and Fig. 3 is a perspective view of the 20 closure-cap of the oil-chamber removed.

Similar letters of reference designate corresponding parts in all of the views of the drawings.

The body or main portion A of my improved 25 wheel is cast in one piece, of iron or other suitable metal, and comprises a hub a, having a central bore b to receive an axle-spindle, and also having an oil-chamber b' surrounding the bore b, and ports b² for feeding oil to the axle-spindle, a rim c, having a flange d, spokes e, interposed between the hub and the rim, an extension e' at the inner end of the hub, provided with a countersink e² to receive the collar usually provided on car-axles, and an annular extension B, which projects outwardly 30 from the outer face of the hub a. The said extension B is provided in its inner side and in alinement with apertures f in the outer end wall of the oil-chamber with grooves or pockets f' for oil, and is also provided with exterior threads g, which extend to the outer face 35 of the hub a and are designed for the engagement of the closure-cap C. The closure-cap, which is best shown in Fig. 3, is cast of one piece of iron or other suitable metal and is provided with interior threads h to engage the threads g of extension B, a plane inner edge i to meet the plane outer face of the hub a, radial lugs j, calculated to afford a secure hold and facilitate placing of the cap on the extension B and the removal of said cap

from the extension, and a central filling-aperture k.

By virtue of the construction of the annular extension B on hub a and the construction of 55 the closure-cap C it will be seen that the latter may be readily screwed on the former and as readily screwed off the same; also that when the cap C is screwed up tight, so that its inner edge bears against the outer face of 60 the hub a, there is no liability of oil leaking from the auxiliary chamber D, formed by extension B and cap C, and no liability of the cap working loose. From this it follows that in my improved self-oiling wheel the use of 65 bolts, gaskets, and similar appurtenances, which tend to materially increase the cost of the self-oiling wheels extant, are unnecessary.

The bore b terminates at its outer end flush 70 with the outer face of the hub, while the annular extension B projects beyond the face of the hub and is provided in its inner side and in alinement with the apertures f in the outer end wall of the oil-chamber b' with 75 grooves f', as before described. By virtue of this construction it will be observed that an oil-chamber D of large capacity is afforded, to which oil is fed through the aperture k in the cap C, that the oil is free to gravitate 80 into the grooves or pockets f' and be led thereby into the chamber b', and that the said grooves or pockets are adapted to carry the oil up as the wheel revolves and feed the same to the upper portion of the chamber b'. 85

When desired, it is obvious that in lieu of providing the body or main portion A of the wheel with spokes e it may be cast solid; also that such other changes or modifications may be made in practice as fairly fall within 90 the scope of my claim.

Having described my invention, what I claim, and desire to secure by Letters Patent, is—

The self-oiling car-wheel comprising the 95 body or main portion made up of the hub provided with the plain outer face, the central bore having its outer end arranged flush with the outer face of the hub, the oil-chamber surrounding and connected with the bore and 100 having the openings f in its outer end wall, and the annular extension B projecting from

the outer face of the hub and out of coincidence with the bore, and having threads at its outer side, and the pockets or grooves f' formed in its inner side and arranged in alignment with the openings f , and the removable, interiorly-threaded cap screwed on the extension B of the body or main portion and provided with a filling-aperture.

In testimony whereof I have hereunto set my hand in presence of two subscribing witnesses.

FREDERICK J. RADFORD.
